CIGARETTE PACKAGE WRAPPER

Clarence A. Winterbourne, Seymour, Conn.

Application September 20, 1939, Serial No. 295,777

4 Claims. (Cl. 206—48)

This invention relates to cigarette packages, and more particularly to an improved outer wrapper for such a package in which said wrapper contains a pocket for receiving a match book or a plurality of loose matches.

It is the usual practice for dealers in cigarettes to hand the customer a book of matches or a plurality of loose matches with each package of cigarettes sold. These matches are ordinarily kept in the customer's pocket with the cigarette package, and are frequently mislaid. By means of the present invention, the above and other disadvantages have been avoided.

One object of this invention is to provide an outer pocket-containing Cellophane wrapper adapted to enclose the inner paper and metal foil wrappers of a cigarette package.

Another object is to provide an improved wrapper of the above nature which is formed from a single strip of Cellophane, folded about the package of cigarettes in such a manner as to entirely enclose it and form a reinforced and "untearable" pocket or receptacle for matches.

A still further object of this invention is to provide an improved cigarette package wrapper of the above nature which will be relatively inexpensive to manufacture, simple in construction, compact, ornamental in appearance, and very efficient and durable in use.

With these and other objects in view, which will appear as the description proceeds, there have been illustrated in the accompanying drawings several forms in which the invention may be conveniently embodied in practice.

In the drawings:

Fig. 1 is a perspective view of a cigarette package and wrapper embodying the features and principles of this invention as they appear with a match book in the pocket of the outer wrapper.

Fig. 2 is a side view of the same with the outer Cellophane wrapper shown in section.

Fig. 3 is a development of the blank from which the improved wrapper shown in Figs. 1 and 2 is formed by folding, together with a portion of a forked tool for making the folds in said blank to produce the match receiving pocket.

Fig. 4 is a view similar to Fig. 3 showing the appearance of the wrapper after the first folding operation has been completed.

Fig. 5 is a partial sectional view of the folded blank, taken on the line 5—5 of Fig. 4.

Fig. 6 is a side view of the wrapper after the front and rear faces have been folded upwardly.

Fig. 7 is a side view of the same after portion of one side have been folded over.

Fig. 8 is a side view of the same after portion of the opposite side have been folded over.

Fig. 9 is a perspective view of a modified form of match-holding package wrapper.

Fig. 10 is a development of the blank from which the wrapper shown in Fig. 9 is folded up.

Fig. 11 is a perspective view of another modified form of cigarette package wrapper in which the match book is inserted between the wrapper and package.

Referring now to the drawings wherein like reference numerals designate like parts throughout the several views, the numeral 10 denotes a package of cigarettes adapted to be enclosed and sealed within the improved match-holding outer wrapper 11, constructed in accordance with the features and principles of this invention. The wrapper 11 is constructed by folding from an elongated flat blank strip 12 of Cellophane (see Fig. 3), or any other waterproof flexible wrapping material which is of the proper size and shape to fit about the package leaving an exterior folded pocket 13 for receiving and retaining a book of matches 14 or a number of loose matches in convenient position for use, and for maintaining them free from moisture.

The blank strip 12 of Cellophane is adapted to be subsequently folded upwardly on a pair of transverse lines 15 and 16 to enclose the base of the package, forming sections 17 and 18 which enclose the front and rear surfaces of the package 10, the portion 19 between the lines 15 and 16 serving to cover the bottom of the package, as indicated in Fig. 6.

Previous to the above mentioned folding operation, the strip 12 is transversely folded intermediate the portion 17 and line 16 upon a pair of lines 20 and 21, as shown in Fig. 3, the portion 22 between these lines being lifted out of the plane of the blank, up and over, as by a leg 23 of a rigid yoke-shaped tool 24, and then folded to the left over the other leg 25 of the tool 24 along the line 20 to cause the section 22 to overlie a portion 26, which is disposed between the lines 16 and 20, and to cause the line 21 to coincide with the line 16. The portion 17 will next be folded back to the right over the leg 23 of the yoke tool 24 along the line 21 into its original plane (see Fig. 4).

In order to prevent the formation of bulky, bulging corners when the blank of the wrapper is folded over the cigarette package, the strip 12 will preferably be cut away as indicated by the V-cuts 27 and 28 connected by the folding line 21.

The strip portions 17 and 18 will next be folded

up into parallelism as indicated in Fig. 6, and the side edges 29 and 30 of the front portion 17, together with double thickness side edges 31 and 32 of the adjacently lying portions 22 and 26 will be folded over the sides of the package 10 as indicated in Fig. 7. The side edges 33 and 34 of the rear portion 18 will then be folded over the opposite sides of the package 10 and sealed with any suitable cement in the usual manner to the previously-folded side edges 29, 30 and 31, 32, as indicated in Fig. 8. A pair of end flaps 35 and 36 will next be folded successively over the top of the package 10 along lines 37 and 38 respectively, as indicated in Fig. 2, the upper flap 36 being cemented to the lower flap 35.

By means of the above construction, it will be seen that the adjacent overlying strip portions 22 and 26 will form a double thickness, practically untearable, reinforced, outer wall for the match receiving pocket 13 surrounded thereby. Moreover, the match pocket 13 will thus serve as a convenient receptacle for detachably holding a book of matches upon the cigarette package 10 until the cigarettes are all used up. Preferably, the book of matches 14 will be inserted in the pocket 13 with its match striking pad 39 at the bottom, whereby the match heads will be protected from moisture, and will always be ready for immediate use in close relationship with the package of cigarettes.

First modified form

In the modified form shown in Figs. 9 and 10, the wrapper 40 is wrapped about the front, sides, and rear surfaces of the package of cigarettes 41 by folding it along the transverse lines 42, 43, 44 and 45. A tab 46 is also provided, which extends laterally from the lower edge of the front portion 47 and is folded upwardly over said front portion along the line 48 to form a match-receiving pocket 49. A pair of sections 50 and 51, on the tab 46, will then be folded along the transverse lines 52 and 53 over the side portions 54 and 55 of the strip 40 and cemented thereto. A plurality of loose matches 56 are herein shown as inserted in the pocket 49, as indicated in Fig. 9.

Second modified form

The form shown in Fig. 11 comprises a rectangular looped band 57 of strip material wrapped about a package 58 of cigarettes. The width of the band 57 is preferably somewhat less than the height of the package 58 so as to form a match receiving pocket 59 between it and the package 58. The band 57 will preferably be of double

thickness with the fold line located at the top to prevent the possibility of tearing when the matches are inserted.

While there have been disclosed in this specification several forms in which the invention may be embodied, it is to be understood that these forms are shown for the purpose of illustration only, and that the invention is not to be limited to the specific disclosure, but may be modified and embodied in various other forms without departing from its spirit. In short, the invention includes all the modifications and embodiments coming within the scope of the following claims.

Having thus fully described the invention, what is claimed as new and for which it is desired to secure Letters Patent, is:

1. In a cigarette package wrapper, a single strip of flat sheet material having portions adapted to be folded about a package of cigarettes to enclose the same and a portion folded upwardly from the bottom portion of said wrapper and having side sections to embrace the sides of said wrapper to form a match receiving pocket for a loose match book to protect the match scratching pad from moisture.
2. In a cigarette package wrapper, a single strip of transparent flat sheet material having two portions adapted to be folded about a package of cigarettes to enclose the same, and a third portion folded upwardly from the bottom edge of one of the other portions and then downwardly to form a double-thickness wall for embracing a plurality of loose matches or a loose match book
3. In a cigarette package wrapper, a single flat strip of material having a front portion, two side portions, and a rear portion adapted to be folded about a cigarette package, and an intermediate portion folded upwardly and then downwardly over itself to form a loose match receiving looped pocket, said intermediate portion having side sections to be folded over the sides of said package.
4. In a cigarette package wrapper, a single strip of material having a front portion, two side portions, and a rear portion adapted to be folded over and about a package of cigarettes, and an intermediate portion folded over itself to form a loose match receiving looped pocket, said folded intermediate portion having side sections adapted to embrace the sides of the package of cigarettes and be cemented thereto.

CLARENCE A. WINTERBOURNE.
